CLAIM

The ornamental design for a lounge chair, as shown and described.

DESCRIPTION

FIG. 1 is a perspective view of the front and side of the lounge chair showing our ornamental design.

FIG. 2 is a side elevation view of the lounge chair, the opposite side being a mirror image thereof.

FIG. 3 is a top down view of the lounge chair.

FIG. 4 is a front elevation view of the lounge chair; and, FIG. 5 is a rear elevation view of the lounge chair.

1 Claim, 5 Drawing Sheets
